FRANCIS K. HOLMESTED, OF QUINNIMONT, WEST VIRGINIA.

RAILROAD-TRACK.

1,077,070.

Specification of Letters Patent.

Patented Oct. 28, 1913.

Application filed March 18, 1913. Serial No. 755,174.

To all whom it may concern:

Be it known that I, FRANCIS K. HOLMESTED, a subject of the King of Great Britain, residing at Quinnimont, in the county of 5 Fayette and State of West Virginia, have invented new and useful Improvements in Railroad-Tracks, of which the following is a specification.

This invention relates to improvements in 10 railroad tracks and particularly to metallic ties having means for separably securing rails thereto and also for positively associating jumper rails with the main track rails.

15 The improved metallic tie and rail securing means are especially adapted for use in mines where it is necessary to frequently change the position of a track bed or track organization or to take up and relay track 20 rails, and, further, to provide for extending the main track through the medium of jumper rails so that the cars may be run up close to the work or located adjacent to a wall of a room of a mine when it is in 25 expedient to lay a full track rail section in the distance between the terminal of the main track bed and the said wall. It is often found necessary to extend a track in 30 a mine within a room to avoid carrying coal, for instance, a distance from the point of mining the same to the car on the main track or to avoid double shoveling, and to 35 meet this contingency jumper or extension rails are applied to the main track rails to permit the car to be run into the room or 40 compartment of the mine beyond the terminal of the main track in order to bring the car close to the working point to directly receive the mined coal or other material or ore.

The present improvement consists in combining with the structure or organization of the railroad track disclosed by my pending applications, Serial Numbers 736,451 and 45 751,377, means in connection with each tie for permitting the application thereto of jumper rails and thereby render the improved railroad track complete in all its details and equip the same in such manner 50 as to fully meet the contingencies of mine railroad track requirements.

In the drawing: Figure 1 is a plan view of a railroad track embodying the improved features. Fig. 2 is a cross-section on the 55 line 2—2, Fig. 1. Fig. 3 is a detail perspective view of a portion of one of the ties.

The numeral 5 designates a tie which is constructed from suitable channel iron or other metal adapted for the purpose. The tie has such general dimensions as to render 60 it convenient for use in a mine and the flanges produced by the channeling of the tie may be of any width or depth and are adapted to be placed directly upon the floor of different portions of a mine. The ties 65 are all of similar structure and when disposed in operative position will be spaced the usual distance. When the ties are placed upon the supporting bed or floor of the mine the flanges thereof will be at the 70 bottom and the lower portions of the flanges, as at 6, will be caused to embed themselves in the floor, the said flanges holding the ties against displacement by having the material of the floor pressed upwardly within the 75 body of each tie between the two opposing flanges at the sides. By this means the tie may be readily placed and automatically secured against movement after placement, and when it is desired to remove the track 80 or to detach the parts thereof and dispose the ties in other places each tie may be readily elevated from the floor and transported to another place or location for further use as may be desired. 85

Each tie is equipped with similar rail fastening means consisting of a flat metal plate 7 having the opposite ends preferably bent inwardly in reverse directions to form rail flange guards or engaging members 8. 90 Primarily each plate from which the fastener is formed is of rectangular contour and of such length that a close engagement will be insured between the inner walls of the inwardly bent guards or engaging members 95 95 and the opposite side edges of the base flange of the rail disposed in the fastening, and owing to the rectangular contour of the plate from which the fastener is formed the inwardly or reversely bent guards or flange engaging members 8 will be projected slightly at opposite side edges 100 of each fastener and thereby increase the purchase or binding action of the said guards or engaging members 8 in diagonal 105 relation on the top surface of opposite portions of the rail flange. The inwardly and reversely bent arrangement of the guards or members 8 also gives a longer bearing between the inner surfaces of the bent walls of 110 the said guards or members relatively to the portions of the rail flange fitted therein, and

a positive or reliable securing of the rails on the ties is thus produced without the necessity of employing spikes or the like.

One fastener on each tie is primarily secured against movement, said fastener being generally indicated by the reference character A, whereas the opposite similar fastener, indicated generally by the reference character B, is pivoted to the tie as at 9 by a suitable pivot pin or rivet inserted through an intermediate portion thereof and the top of the tie. This pivoted fastener B is shiftable to bring the same in proper position for introduction of the rail flange there-in, and after the rail has been engaged therewith the said fastener is swung on the tie and by such operation the rail is simultaneously secured and at the same time is drawn into proper gage relatively to the 20 companion rail on the opposite extremity of the tie and thus the necessity of measuring or gaging the rails after they have been disposed in the fasteners is avoided. When the pivoted fastener B is swung around into 25 locking position relatively to the rail it is securely held against movement by a locking pin or latch projection 10 carried at one end of a spring arm or plate 11 secured to the under side of the tie at the opposite end, as 30 at 12, the pin or projection 10 being movable through an opening 13 in the top of the tie and also adapted to engage a corresponding opening 14 in the plate or body of the fastener B. In order to release the pin or 35 projection 10 from the fastener B, another opening 15 is formed in the top of the tie through which a pick point or other implement may be inserted to press the spring arm or plate downwardly and correspondingly depress the said pin or projection to 40 disengage the same from the opening 14 in the fastener, and after this release has been effected the fastener may be turned as may be desired to detach the rail therefrom.

45 From the foregoing it will be seen that each fastener is disposed directly upon the top portion of the tie, there being no devices of any kind interposed between the fastener and the tie, and consequently there 50 is no danger of a break-down or distortion of intermediate parts and modification of the track level, and the track rails will be maintained in proper relative positions in a horizontal plane with material advantages 55 in the movement of rolling stock or cars thereover. When the fasteners A and B are in engagement with the rails they are disposed in converging diagonal planes relatively to each other, as clearly shown by 60 Fig. 1, and hence the rails will be prevented from slipping or becoming in the least displaced and will always be maintained in proper relative gage.

Each tie has an abutment or guard 16 rising 65 therefrom inside of each fastener, the

abutments or guards 16 of the tie having free ends extending outwardly, as at 17. These abutments or guards 16 may be applied to the tie, but it has been found that they can be economically formed by cutting the top portion of the tie at a suitable distance inwardly from each fastener and then striking the cut portion upwardly and bending the same as shown so as to dispose the free end 17 of each abutment in a position to squarely engage with or bear against a jumper rail 18 associated with each main track rail. These jumper rails 18 are used to extend the main track beyond its terminal into rooms, compartments or places where the distance between the terminal of the main track and the farther wall of the room or compartment is less than the length of a standard rail section so that the car may be moved up close to the work or the point where the coal or other ore is being mined to avoid the delay incident to transferring the coal or ore to the car at a distance from the working point and also to overcome the necessity of double shoveling.

In applying the jumper rails 18 the heads of the rails are inserted between the base flanges and the balls or heads of the main track rails with the base flanges of the jumper rails arranged so that the edges thereof at one side will bear on the ties and the other edges stand uppermost, and when so disposed the abutments or guards 16 will firmly bear against the central portions of the base flanges and securely hold the jumper rails in association with the main track rails. Under these conditions the side portions of the heads or balls of the jumper rails will be clear of the treads of the car wheels at points beyond the terminals of the main track rails, and the flanges of the car wheels will extend into the space between the heads and flanges of the jumper rails and engage the webs of the latter rails. Beyond the terminals of the main track rails the jumper rails are supported on the mine floor and will positively sustain the weight of the cars moving thereover and, furthermore, the cars will readily pass from the main track rails onto the jumper rails and from the latter back to the main track rails without liability of derailment of the cars.

In applying the rails to the tie extremities having thereon the fixed fasteners A, each tie is turned in such position that the opening between the guards or engaging members 8 will receive the base flanges of the rails, and after the rail has been seated or pushed into the seat of each fixed fastener 125 formed between the said guards or engaging members 8, the tie is bodily turned so as to change its position at an angle of application to a direction transverse of the floor or bed or in a plane at right angles to the rail 130

in order to cause the guards or engaging members 8 to tightly embrace the opposite portions of the base flange of the rail.

In applying the rails to the pivoted fasteners B the said fasteners are released and turned at a proper angle with relation to the top of the tie, and after the rails are inserted in the pivoted fasteners the latter are each turned with the rails disposed therein to cause the same to extend diagonally across the top of the tie in converging planes relatively to the fixed fasteners, and the instant that the opening 14 in each fastener registers with the opening 13 in the tie, the pin or projection 10 of each lock will immediately snap upwardly and secure the pivoted fastener against movement and at the same time the rail will be drawn into proper gage relatively to the opposing rail on the opposite extremity of the tie and also in alignment with other rails that may have been laid in connection with the pivoted fasteners. When the track is taken up or disorganized the rail engaging the pivoted fasteners will be first removed by shifting the said fasteners to release positions and the rails detached therefrom, and afterward the remaining rails engaging the fixed fasteners will be released by swinging the ties thereunder to a proper angle to release the guards of the fixed fasteners from the rails and permit the latter to be lifted out or detached. The jumper rails may be readily associated with the main track rails or detached therefrom by the very simple operation hereinbefore explained and the abutments or guards 16 when not in use as the securing means for the jumper rails will not in the least interfere with the fasteners A and B in performing their functions relatively to the main track rail.

From the foregoing it will be seen that a tie is provided equipped with devices of a simple character to meet the various contingencies of mine railroading or track construction at a comparatively small cost. While the improved rail fastening means and ties as thus explained have been par-

ticularly devised for mine railways or tracks, it will be understood that they might be adopted in other railway constructions where it is desired to shift a railroad track from one place to another in an expeditious and positive manner, and, furthermore, the same essential features might be adopted in railway constructions to facilitate the removal and replacement of rails that may become worn.

What is claimed is:

1. A railroad tie having rail engaging fasteners on opposite extremities thereof, the one fastener being fixed on the tie and the other fastener pivoted on the tie, and upwardly projecting abutments or guards disposed a suitable distance inside of the fasteners to engage portions of jumper rails.

2. In a railway track, the combination of a tie having fasteners on opposite extremities thereof with engaging means for main track rails, one fastener being fixed on the tie and the other fastener pivoted on the tie, and upwardly projecting outwardly extending abutments to engage portions of jumper rails, the said abutments rising from the tie at points inside of the fasteners and at relative distances from the latter.

3. In a railway track, the combination of a plurality of ties having fasteners on opposite extremities provided with rail engaging means, one fastener being permanently fixed on each tie and the other fastener being pivoted on each tie, guards rising from the ties inside of the fasteners and at relative distances from the latter, main track rails separately engaging the said fasteners, and jumper rails interposed between the inner portions of the main track rails and the guards to extend the track beyond the terminals of the main track rails.

In testimony whereof I have hereunto set my hand in presence of two subscribing witnesses.

FRANCIS K. HOLMESTED.
